J. J. RONAYNE,
ELECTRICAL ILLUMINATING DEVICE,
APPLICATION FILED APR. 18, 1919.

1,321,337.

Patented Nov. 11, 1919.

Fig. 3.

Inventor,
John J. Ronayne
by *Albert Malcomson*

his Attorney.

UNITED STATES PATENT OFFICE.

JOHN J. RONAYNE, OF NEW YORK, N. Y.

ELECTRICAL ILLUMINATING DEVICE.

1,321,337.

Specification of Letters Patent. Patented Nov. 11, 1919.

Application filed April 18, 1919. Serial No. 291,064.

To all whom it may concern:

Be it known that I, JOHN J. RONAYNE, a citizen of the United States, residing in the city, county, and State of New York, have 5 made certain new and useful Improvements in Electrical Illuminating Devices, and hereby declare the following specification to be a description thereof, reference being had to the accompanying drawings.

10 The object of my invention is to produce a pleasing reflection and distribution of light by means of a submerged electrical bulb and mirror inclosed within a vase or other structure, from the open top of which 15 projects a foraminous foliage structure. All of which is hereinafter more specifically set forth.

In the drawings:—

Figure 1 is an elevation of my new device, 20 Fig. 2 is a vertical cross-section through the center of Fig. 1 and

Fig. 3 is a top view of Figs. 1 and 2 with the upper light distributing structure removed.

25 A represents a hollow structure in the form of a vase which is made of any desired material. I preferably make this vase of reasonably thin metal. But it may be constructed of papier-mâché or like material.

The bottom *a*, of this vase is pierced at *b*, for the admission of covered wires *c*, *c*, to conduct electricity from any available source; which is not shown.

30 Within the vase just above the contracted part I place a circular mirror *d*, adapted to reflect upward.

The center of the mirror *d*, is pierced at *e*, for the reception of an electric light socket *g*, into which the electric light bulb *h*, is screwed.

Above the electric light bulb is a supporting frame comprising a central ring *l*, and arms *m*, *m*, extending therefrom to an outer 45 ring *o*, which rests on the interior of the flaring mouth of the vase *A*. The ring *o*, is held in position by flexible catchés *p*, *p*, secured to the inner face of the vase.

Above the mouth of the vase is a light 50 distributing structure *B*, formed of broadened leaves *r*, *r*, and stems carrying flowers *s*, *s*, alternating between the leaves.

In the artificial flowers *s*, may be used small electric light bulbs *t*, *t*, if it is so de-

sired. In such cases the small electric light 55 bulbs will be supplied with electric current through wires *w*, *w*, originating in the body of the vase.

The use of auxiliary lights in the flowers of the open work structure is an additional 60 feature and adds to the general effect.

The arms *m*, *m*, of a supporting frame may serve also to carry a thin screen of a colored medium *n*, through which light will readily pass, such as tissue paper, which will 65 heighten the effect of the device.

By this means I am enabled to get light effects of new and varied kinds.

In having the light distributing superstructure *B*, constructed so it is detachable 70 from the vase *A*, I am enabled to obtain ready access to the interior of the vase, and to vary the style of superstructure.

It will be understood that I do not limit myself to any specific design for either the 75 vase or base or the deflecting upper portion, as it is apparent that the superstructure may be varied so long as the light distributing part is foraminous and the source of light is inclosed within the lower inclosing structure with means below it for reflecting the light into the open work part above.

What I claim as new and desire to secure by Letters-Patent is:

1. In an electric light distributing device, 85 a hollow containing receptacle inclosing a circular mirror pierced at its center with a circular opening, an electric light bulb protruding through said opening, surrounded by said mirror and a deflecting foraminous 90 structure in simulation of foliage and flowers above said light and reflector, as shown and described.

2. In an electric lighting device, an inclosed light compartment with an open top 95 having a flat upwardly reflecting ring or mirror, located therein adapted to surround an electric light bulb, and a superimposed foraminous metal structure in simulation of foliage and flowers, detachably resting on 100 said inclosed light compartment, substantially as shown and described.

3. An electric lighting device comprising a hollow circular inclosing vase structure carrying within it an electric light bulb and 105 a pierced upwardly reflecting mirror, a removable superstructure of foliage and flowers, auxiliary electric bulbs in said flowers

and means for conveying the electric supply from the inclosed wires to the auxiliary lights, substantially as shown and described.

4. An electric lighting device comprising a hollow containing receptacle, an inclosed electric light bulb, a superimposed light dis-

tributing foraminous structure simulating leaves and flowers and an intermediate light coloring medium between the electric bulb and the said superstructure, substantially as 10 and for the purposes described.

JOHN J. RONAYNE.
